UNITED STATES PATENT OFFICE.

ANDREW KAY WOMRATH, OF NEW YORK, N. Y.

DESIGN FOR A BADGE.

SPECIFICATION forming part of Design No. 31,426, dated August 22, 1899.

Application filed July 24, 1899. Serial No. 725,010. Term of patent 31 years.

To all whom it may concern:

Be it known that I, ANDREW KAY WOMRATH, a citizen of the United States, residing in the city of New York, borough of Manhattan, State of New York, have invented and produced a certain new and original Design for a Badge, of which the following is a specification, reference being had to the accompanying drawings, forming a part hereof.

10 This invention consists in the design for a badge shown in the accompanying drawings, in which—

15 Figure 1 is a front elevation of a badge embodying my design, and Fig. 2 is a cross-section of the same.

The upper part A of the design represents a cannon; upon which are superimposed laurel-branches B. The lower part C is a plane surface or plate, and between the upper and lower parts are represented chains, as at D. 20

The leading feature of the invention consists of the badge herein shown and described.

I claim as my invention—

The design for a badge, substantially as shown and described. 25

This specification signed and witnessed this 20th day of July, A. D. 1899.

ANDREW KAY WOMRATH.

In presence of—

ANDREW H. SCOBLE,
JOHN M. SCOBLE.
